WRITING INSTRUMENT

Robert W. Randolph, Milton, Wis., assignor to
 The Parker Pen Company, Janesville, Wis., a
 corporation of Wisconsin

Application October 3, 1951, Serial No. 249,503

10 Claims. (Cl. 120—42.03)

1 This invention relates generally to writing instruments and has to do particularly with a writing instrument of the type including a casing in which is mounted a writing point adapted to be projected from the casing into a writing position or retracted into a concealed and protected position within the casing.

One of the objects of my invention is to provide an improved writing instrument of the foregoing character.

Another object is the provision of a writing instrument of the foregoing character having a casing with extensible and contractible casing sections which can be telescoped over one another so that the instrument when contracted is of minimum length for insertion in one's pocket, and when the sections are extended, the instrument is of convenient length for holding in the hand for writing purposes, and in which the writing point is projected from the casing by manipulation of the casing sections after the latter are moved to extended position.

A further object of the invention is the provision of a writing instrument of the character referred to in which the writing point is automatically locked in writing position when manipulated to effect the projecting movement thereof so that it cannot be retracted into the casing by pressure applied to the point in a writing operation.

Still another object is the provision of a writing instrument of the character referred to in which the writing point can be projected out of the casing only after the casing sections have been extended, whereby the point is not likely to be projected accidentally.

Still another object is the provision of a writing instrument of the character referred to in which the writing point must be completely retracted into the casing before the manipulation effecting the contracting movement of the casing sections can be accomplished, thereby minimizing the likelihood of inserting the instrument in a pocket with the writing point projected, with consequent elimination of the probability of soiling the clothes of the user such as may occur if the instrument is inserted in the pocket with the writing point projected.

A further object is the provision of a writing instrument of the character referred to in which there is minimum resistance to extension and contraction of the casing sections.

A still further object is the provision of a writing instrument having a casing and a writing unit including a writing point for projection from

2 the casing, in which the casing includes separable parts for exposing the interior of the casing and thereby facilitating insertion of the unit in the casing and removal therefrom, and in which means is provided for frictionally retaining the unit in the casing under normal conditions but permitting the unit to be removed in response to force applied for that purpose.

Another object is the provision of a writing instrument of the foregoing character of exceedingly simple construction and containing a minimum number of parts.

Other objects will appear from the following description in conjunction with the accompanying drawings, in which:

Fig. 1 is a side elevational view of the writing instrument of the present invention in contracted condition;

Fig. 2 is a side elevational view of the instrument in extended condition;

Fig. 3 is an enlarged, longitudinal sectional view of the instrument in contracted condition;

Fig. 4 is a sectional view taken on line 4—4 of Fig. 3;

Fig. 5 is a sectional view taken on staggered line 5—5 of Fig. 3;

Fig. 6 is a sectional view taken on line 6—6 of Fig. 3;

Fig. 7 is a longitudinal view of the instrument showing certain outer portions in section and certain inner portions in elevation, with the instrument in contracted position, the view being taken at right angles with respect to the view of Fig. 3;

Fig. 8 is a view similar to Fig. 7 but with the instrument in extended position, before relative rotation of the casing sections has taken place and with the writing point retracted into the casing; and

Fig. 9 is a view similar to Fig. 8 but after relative rotation of the casing sections has taken place and with the writing point projected from the casing.

The present invention is particularly well adapted to a ball point writing instrument, and for that reason such type of writing instrument is disclosed herein. In the case of a ball point writing instrument, it is desired that the writing point be retracted into the casing when the instrument is not in use and is to be placed in the pocket of the user so that the point will not soil the clothes.

Referring in detail to the drawings the instrument as a whole is shown at 12 in Figs. 1 and 2, Fig. 1 showing the instrument in contracted position and of reduced length so that it can be con-

veniently placed in a pocket or in a purse. In Fig. 2 the instrument is illustrated in extended position for writing, and as observed in the two figures in extended position the instrument is of substantially greater length than when contracted. Also it will be observed that when the instrument is in contracted position (Fig. 1) the writing point is retracted into the pen casing so that the writing point will not soil the clothes of the user when inserted in the pocket, as mentioned above. The writing point is of course projected for writing purposes, as illustrated in Fig. 2, being projected by relative movement of the portions of the instrument associated with the operation of extending the instrument.

The casing of the instrument is made up of a forward casing section 14 and a rear casing section 16, the two sections being associated for sliding telescopic movement relative to one another in a longitudinal direction. The rear casing section substantially encloses the forward casing section when the instrument is in contracted position whereby the instrument is of minimum length when contracted.

The two casing sections 14 and 16 together form a casing for containing a writing unit, indicated in its entirety at 18, which may be of any suitable type. Briefly the writing unit 18 includes a reservoir element 20 of cylindrical shape, providing an ink reservoir, a writing point 22 having a ball 24 mounted in its writing tip, and a feed 26 for feeding the writing fluid from the reservoir 20 to the writing point. The reservoir element 20 may be detachable from the feed 26 for replacement when the ink is exhausted.

The forward casing section 14 takes the form of an assembly including a nose member 28, a body sleeve 30 and a slide sleeve or cover sleeve 32. The exterior surface of the nose member 28 tapers to a writing end of substantially reduced diameter, and is of relatively heavy and rugged wall construction, as shown for example in Fig. 3. The nose member 28 includes a small diameter opening or bore 34 at its forward writing end, of such diameter as to freely receive the feed 26 for projection of the writing point 22 therethrough so that the ball 24 is exposed for writing purposes as illustrated in Fig. 2. Rearwardly of the small diameter bore 34 is an enlarged bore 36 for accommodating the forward end of the reservoir element 20 when the writing unit is moved forwardly therein in the movement of projecting the writing point through the bore 34. The rear end of the nose member 28 is of slightly reduced external diameter and provided with external threads 38 for receiving the internal threads 40 at the forward end of the body sleeve 30, for rigidly connecting the nose member and body sleeve together.

The nose member 28 and body sleeve 30 form the body of the instrument, supporting the rear casing section and the writing unit. The body sleeve 30 may be imperforate throughout its extent except for an aperture 42 adjacent its rear end into which is inserted a pin 44 extending radially inwardly from the sleeve for extending into certain slots in other portions of the pen, as will be referred to in detail later, for aiding in guiding the casing sections and for aiding in moving the writing unit for projection and retraction of the writing point through the opening 34 in the nose member 28.

All of the operating mechanism of the instrument is concealed by portions of the casing sections as will be apparent as the description

proceeds, and all portions of the instrument that are exposed or may be exposed are given a finished appearance. To the end of imparting a finished appearance to the body sleeve 30, the latter is encased in the cover sleeve 32 which snugly and removably fits the body sleeve. The forward end of the cover sleeve 32 is turned in to form a flange 48 which is clamped between the nose member 28 and the forward end surface of the body sleeve 30. Thus the cover sleeve 32 is retained in proper and fixed position relative to the body sleeve 30 as well as the nose member 28. The cover sleeve 32 is also effective for retaining the pin 44 in place in the aperture 42, the pin if desired being otherwise removable outwardly from the aperture 42 so as to facilitate assembly and disassembly of the pen. Thus the cover sleeve covers the body sleeve and imparts a finished appearance to that portion of the instrument, and conceals the pin 44 which constitutes an element of the operating mechanism of the instrument.

The threads 38 and 40 enable detachment of the nose member 28 from the body sleeve 30 and from the slide sleeve 32 to enable the writing unit to be inserted in and removed from the casing as is necessary upon exhaustion of the supply of writing fluid in the reservoir. Such removal and replacement can be made with facility upon removal of the nose member 28 merely by holding the instrument in one hand and grasping the writing unit in the other hand and pulling it out of the casing.

The reservoir element 20 is frictionally fitted in and carried by a spiral sleeve or driven sleeve 50, the latter directly engaging the inner surface of one of the elements making up the rear casing 16 as will be referred to later. The driven sleeve 50 at any convenient location therein such as adjacent the forward end (Fig. 3) is provided with a plurality, e. g., four, of longitudinal slots 52 spaced circumferentially of the sleeve and preferably arranged in pairs, the two slots of each pair (one pair shown in Fig. 3) defining therebetween a strip 54 which is bent or depressed radially inwardly for forming a friction gripping area engageable with the exterior surface of the reservoir element. These areas 54, one on each of opposite sides of the driven sleeve, by frictionally engaging the reservoir element, normally retain it in place in the sleeve but permit removal of the writing unit upon application of sufficient pressure for that purpose, such as by withdrawing by the hand.

In the normal operation of the instrument the writing unit 18 and the driven sleeve 50 move together as a single unit in the projecting and retracting movements of the writing unit. Therefore the writing unit and driven sleeve together form, in effect, a single unit so far as concerns the projection and retraction of the point. The driven sleeve 50 and the writing unit are arranged for conjoint longitudinal sliding movement with respect to the instrument as a whole for producing projecting and retracting movements, while they also rotate relative to one of the casing sections, as will be explained in detail later. A novel arrangement of cam means is provided for producing the projecting and retracting movement of the writing unit as will be explained fully in a later part of the description.

The spiral or driven sleeve 50 is provided with a helical or so-called "spiral" slot 56 extending circumferentially of the sleeve slightly more than

180° so that a full 180° of relative rotational movement between the casing sections is permitted, consideration being given to the thickness of the cam means working in the slot which is constituted by the pin 44 which may also be referred to as a cam element. The pin 44 (Fig. 3) is of proper radial length to extend into the spiral slot 56 to a point adjacent the cartridge 20. The spiral slot 56 progresses clockwise and rearwardly as viewed from the writing point end of the instrument. The slot is shown in Fig. 5 which is a view on staggered line 5—5 of Fig. 3, following the inclination of the slot, the shape of the slot being shown to better effect in Figs. 7-9. In Fig. 3 only the ends of the slot are indicated, the remaining portion being in that portion of the sleeve removed from the figure.

The driven sleeve 50 is also provided with a radially outwardly extending projection 58 which may be formed integrally with the sleeve by any appropriate shaping operation. This projection 58 is in effect a pin and also forms a cam element, extending into a slot 82 formed in one of the elements of the rear casing section as will be referred to later. The projection 58 is positioned adjacent the rear end of the driven sleeve, and as here shown is at least as far rearward as the rear end of the spiral slot 56. In the contracted position of the instrument the projection 58 is disposed rearwardly of the pin 44.

The rear casing section 16 is provided with elements for cooperating with other elements in the forward casing section for moving the writing unit in projecting and retracting directions, and also is provided with a sleeve for telescoping over and concealing the greater portion of the forward casing section when the instrument is in contracted position. The rear casing section 16 is made up of an inner sleeve or drive sleeve 60 and an outer sleeve 62 secured together by connecting means which will be described at this point so that uninterrupted attention can later be given to the main elements of the instrument. The sleeves 60 and 62 are provided with inturned flanges 64 and 66 respectively at their rear ends, fitted together and resting on a shoulder 68 formed on an annular plug 70 having interior threads for threaded receiving a screw bushing 72 having both exterior and interior threads. The outer end of the screw bushing 72 diverges rearwardly forming an exterior surface 73 for engagement with a sleeve ring 74, the latter having one end engaging the flange 66 and provided at its other end with a tapered-surface opening 76 complementary in shape to and engaged by the surface 73. The outer end of the screw bushing 72 is provided with a kerf 78 for use in threading the bushing into the plug 70. Upon being threaded down, the screw bushing acting through the cap element 74 effectively secures the sleeves 60 and 62 together and with the plug 70. Finally a screw 80 is threaded into the interior threads of the bushing 72 for providing a finished appearance to the rear end of the rear casing section.

The drive sleeve 60 of the rear casing section cooperates with the forward casing section in the extension and contraction movements of the casing sections for projecting and retracting the writing point through the opening 34 of the nose member 28. This sleeve is so shaped as to fit snugly in the body sleeve 30 but with freedom for sliding and rotational movement therein. The sleeve 60 is provided with a slot 82 for producing certain camming effects as will be referred to later, and for guiding the casing sections in their

expanding and contracting movements, the slot having a longitudinal portion 84 and a circumferential portion 86 at the forward end of the longitudinal portion. The longitudinal portion 84 of the slot extends from a point adjacent the rear end of the sleeve to a point closely adjacent the forward end thereof where the circumferential portion 86 of the slot communicates with the longitudinal portion and continues around the sleeve in a plane perpendicular to the longitudinal axis of the instrument for slightly more than 180° to accommodate relative rotation of the casing sections a full 180° in the manner referred to in connection with the spiral slot 56. In the assembled instrument, the circumferential portion 86 of the slot 82 is disposed on the same side of the instrument as is the spiral slot 56. The longitudinal portion 84 of the slot extends parallel with the axis of the instrument so that in the extending movement of the casing sections they are extended directly longitudinally without rotation. The pin 44 secured in the body sleeve 30 extends through the longitudinal portion of the slot 82 when the casing sections are contracted (Fig. 3) but when the casing sections are extended (Fig. 8), the pin 44 is in position for moving into the circumferential portion 86 of the slot in response to relative rotation of the casing sections. The projection 58 also extends into the longitudinal portion of the slot 82 but as will be referred to later, it does not move into the circumferential portion of the slot.

The drive sleeve 60 receives the driven sleeve 50 in engagement with its inner surface and the two sleeves are fitted for free relative sliding movement although there is no relative rotational movement between the drive sleeve 60 and the driven sleeve 50.

When the instrument is contracted, the outer sleeve 62 encases all of the other sleeves, and it will be evident that it conceals all of the operating mechanism. When the instrument is extended all of the operating mechanism is concealed by the outer sleeve 62 and the cover sleeve 32. The two sleeves 62 and 32 therefore conceal all of the operating mechanism and provide a finished appearance to the instrument.

When the instrument is in contracted position (Figs. 3 and 7) it will be noted that the writing point 22 is retracted through the bore 34 into the casing. Also it will be noted that the pins or projections 44 and 58 are both adjacent the rear end of the longitudinal portion 84 of the slot 82. These projections are spaced apart a distance at least as great as the extent of movement of the writing unit in the projecting and retracting movements of the latter.

To extend the instrument and project the writing point, the first step is to grasp the casing sections and pull them in extending direction. This results in relative longitudinal movement of the sections without relative rotational movement since the pin 44 is fixed in the sleeve 30 and rides in the longitudinal portion 84 of the slot 82. The extending movement is limited by the pin 44 engaging the forward end of the longitudinal portion 84 of the slot 82. The writing unit in the extending movement just referred to does not move relatively to the forward casing section, being restrained by the pin 44 engaging the spiral slot 56 and since the spiral or driven sleeve 50 and the writing unit are restrained against rotational movement by the projection 58 in the longitudinal portion 84 of the slot 82, the writing unit remains stationary relatively to the

forward casing section. The only movement thus permitted in the initial portion of extending and projecting operation is rearward movement of the rear casing section relative to the forward casing section.

The position of the parts after the extending movement as above referred to is shown in Fig. 8 where the pin 44 is at the forward end of the portion 84 of the slot 82 and in position to move into the portion 86 of the slot. In this position 10 of the parts also the projection 58 is near the forward end of the portion 84 of the slot, but spaced rearwardly therefrom the same distance as the spacing thereof when the sections are contracted (Figs. 3 and 7).

With the parts in extended position as just referred to and as shown in Fig. 8, and for the purpose of projecting the writing point, the rear casing section is rotated relatively to the forward casing section in a right-hand screw threading motion, i. e., it is rotated clockwise as viewed from the rear of the instrument. The pin 44 thus rides into the circumferential portion 86 of the slot 82. The pin 44 it will be recalled also extends into the spiral slot 56 and because of the relative rotational movement between the casing sections, the pin 44 rides in the spiral slot, and since the driven sleeve 50 is prevented from rotating by the engagement of the projection 58 in the longitudinal portion 84 in the slot 82, the effect is a camming action between the pin 44 and the spiral slot 56, moving the driven sleeve 50 and the writing unit forwardly of the casing for projecting the writing point through the bore 34. The projecting movement of the writing unit results in a component of longitudinal movement thereof during which the projection 58 continues to ride in the longitudinal portion 84 of the slot 82 to a position approaching the forward end thereof as shown in Fig. 9. The same effect can be procured by placing the projection 58 rearwardly of the position shown so that the spacing between it and the pin 44 is greater than the longitudinal component of dimension of the spiral slot, the consideration being that projection 58 is placed rearwardly sufficiently that it is not limited in its relative forward movement by the forward end of the portion 84 of the slot 82.

Thus the slot 56 constitutes a cam element having both longitudinal and circumferential components, the pin 44 fixed in the body sleeve 30 constitutes a cam element having a longitudinal component, and the projection 58 and the longitudinal portion 84 of the slot 82 together constitute a cam element having a circumferential component.

When the writing unit is in projected position as described and as illustrated in Fig. 9, the writing unit is locked against retraction by any force applied longitudinally to the writing point and therefore the pressure applied to the writing point in writing, regardless of its force, will not retract the writing unit into the pen casing. The force applied longitudinally to the writing point as in writing is resisted by the pin 44 which is fixed in the body sleeve 30, and by the edge of the portion 84 of the slot in cooperation with the projection 58. The pin 44 restrains the writing unit from longitudinal movement and the portion 84 of the slot cooperating with the projection 58 restrains the writing unit from relative rotation between the writing unit and the rear casing section. In order for the writing unit to be retracted it must be rotated in order to enable the pin 44 to

ride in the spiral slot 56 and since it is held against rotation, it is restrained against retraction by the force applied as mentioned when the casing sections are expanded and relatively rotated. The writing point can be retracted only by relatively rotating the casing sections in the reverse direction from that employed in projecting the writing point, namely, by rotating the rear casing section relatively to the forward casing section by a left-hand screw threading motion (as viewed from the rear of the instrument). This relative motion places the pin or projection 44 in or in line with the longitudinal portion 84 of the slot 82. Thereafter the casing sections may be contracted by telescopically moving them together in a longitudinal direction. The casing sections cannot be contracted when the writing point is projected. The sections must first be rotated for retracting the writing point, after which they can be contracted.

It will be evident from the foregoing that the probability of inserting the instrument in the pocket while the writing point is projected, is virtually eliminated. It is desirable of course that such occurrence be avoided so that the clothes of the user will not be soiled. At no time when the casing sections are fully retracted or only partially retracted can the writing point be projected. The writing point can be projected only after the casing sections are fully extended and rotated relatively to one another. Thus, if the instrument while in the pocket should become partially extended, the writing point would not be projected so as to soil the clothes, and it is virtually impossible for the casing sections to be extended and rotated by accident when in the pocket.

I claim:

1. In a writing instrument, a casing including a forward section and a rear section, the forward section having an opening at its forward writing end, and the rear section being telescopically slideable on the forward section, a writing unit having a writing point and mounted in the casing for longitudinal sliding movement therein for projection and retraction of the writing point through said opening, and means interconnecting said sections and unit operative for moving the unit and projecting the writing point in response to relative movement between the sections, said means including an inclined cam element on said writing unit adjacent the rear end thereof, a cam element on one of the sections having a straight longitudinal portion and a circumferential portion adjacent one end thereof lying substantially in a plane perpendicular to the longitudinal axis of the section, and a cam element on the other section engageable with said first two cam elements, said last cam element and circumferential portion being relatively positioned for interengagement only when the casing sections are extended.

2. In a writing instrument composed of three main parts including a forward and a rear casing section and a writing unit, the casing sections forming a casing containing the unit, the forward casing section having an opening at its forward writing end, and the rear casing section being telescopically slideable on the forward section for longitudinal extension and contraction of the sections, the unit having a writing point and being mounted in the casing for longitudinal sliding movement therein for projection and retraction of the writing point through said open-

ing, and cam means interconnecting the three parts comprising a first cam element on one of the parts having a longitudinal and a circumferential component, a second cam element on another of the parts having a longitudinal portion of substantial length and a circumferential portion at one end of the part, and a third cam element on the third part engageable with the first and second cam elements, said cam means being relatively positioned as to be operative for retaining said sections against relative rotational movement in the extension and contraction movements thereof, and enabling relative rotational movement of the sections only when in extended position and retaining the sections against relative longitudinal movement when extended and relatively rotated, and operative for moving the unit and projecting the writing point in response to relative rotation of the sections when in extended position.

3. In a writing instrument, a casing including a forward section having an opening in its forward writing end, and a rear section telescopically slidable on the forward section for extension and contraction of the sections, a writing unit having a writing point and slidably mounted in the casing for projection of the point outwardly through said opening and retraction inwardly therethrough, one of said sections having a slot with a longitudinal portion and a circumferential portion at one end thereof, said unit having a spiral slot, the other section having a projection extending into both of said slots, said projection being positioned relative to said other section for positioning in said longitudinal portion when the sections are contracted and for positioning in said circumferential portion only when the sections are extended, said unit having a projection extending into said longitudinal slot portion on the side of the first projection opposite said circumferential slot portion, whereby the casing sections are extendible longitudinally after which relative rotation of the sections moves said unit for projection of its writing point through said opening.

4. In a writing instrument, a casing including a forward section having an opening in its forward writing end, and a rear section telescopically slidable on the forward section, a unit having a writing point slidable in the casing for projection of the point outwardly through said opening and retraction inwardly therethrough, said rear section having a slot including a longitudinal portion and a circumferential portion at the forward end of the longitudinal portion, said unit having a spiral slot adjacent its rear end, said forward section having a projection extending into both of said slots, and said unit having a second projection extending into the slot in said rear section rearwardly of said first projection, said sections being thereby extendible with both of said projections riding in said longitudinal portion of the slot, whereafter upon relative rotation of the sections said first projection rides in said circumferential portion of the slot and in said spiral slot and said second projection remains in said longitudinal portion of the slot in the rear section and retains said unit against rotation relative to said rear section.

5. In a writing instrument, a casing including a forward section and a rear section telescopically slidable on the forward section, said forward section including a nose member having an opening at its forward writing end, and a body sleeve detachably connected to said nose member and

extending rearwardly therefrom, said rear section including a drive sleeve telescopically slidable in said body sleeve, a writing unit encased generally in said body sleeve for sliding movement therein and having a writing point positioned for projection and retraction through said opening in response to movement of the unit, said drive sleeve having a slot including a longitudinal portion and a circumferential portion at the forward end of the longitudinal portion, said unit having a spiral slot adjacent its rear end, said body sleeve having a fixed projection adjacent its rear end extending into and relatively slidable in both of said slots, and said unit having a fixed projection extending into and relatively slidable in said longitudinal portion of the slot in the drive sleeve rearwardly of said first projection.

6. In a writing instrument, a casing including a forward section and a rear section telescopically slidable on the forward section, said forward section including a nose member having an opening at its forward writing end, and a body sleeve detachably connected to said nose member and extending rearwardly therefrom, said rear section including a drive sleeve telescopically slidable in said body sleeve and having a slot with a straight longitudinal portion and a circumferential portion adjacent one end of the longitudinal portion, a driven sleeve having a spiral slot and slidably disposed in said drive sleeve, a writing unit having a writing point and frictionally held in said driven sleeve for movement therewith for projection and retraction of the writing point through said opening, said body sleeve having a fixed pin adjacent its rear end extending into both of said slots, and said driven sleeve having a fixed pin extending into said longitudinal portion of the slot in the drive sleeve rearwardly of said first fixed pin.

7. In a writing instrument, a casing including a forward section and a rear section telescopically slidable on the forward section, said forward section including a nose member having an opening at its forward writing end, a body sleeve detachably secured to said nose member and extending rearwardly therefrom, a cover sleeve detachably fitted on said body sleeve and having a portion detachably secured between said nose member and body sleeve, said rear section including a drive sleeve telescopically slidable in said body sleeve with a slot having a longitudinal portion and a circumferential portion at the forward end thereof, a driven sleeve having a spiral slot slidably disposed in said drive sleeve, a writing unit having a writing point and frictionally held in said driven sleeve for movement therewith for projection and retraction of the writing point through said opening, said body sleeve having a fixed projection adjacent its rear end extending into both of said slots, and said driven sleeve having a fixed projection extending into said longitudinal portion of the slot in the drive sleeve rearwardly of said first fixed projection.

8. In a writing instrument, a casing including a forward section and a rear section telescopically slidable on the forward section, said forward section including a nose member having an opening at its forward writing end, a body sleeve detachably secured to said nose member and extending rearwardly therefrom, a cover sleeve detachably fitted on said body sleeve and having a portion detachably secured between said nose member and body sleeve, said rear section includ-

ing a drive sleeve and an outer sleeve, the drive sleeve being telescopically slidable in said body sleeve and having a slot with a longitudinal portion and a circumferential portion at the forward end thereof, the outer sleeve being telescopically slidable over said cover sleeve, a driven sleeve having a spiral slot and slidably disposed in said drive sleeve, a writing unit having a writing point and frictionally held in said driven sleeve and movable therewith for projection and retraction of the writing point through said opening, said body sleeve having a fixed projection adjacent its rear end extending into both of said slots, and said driven sleeve having a fixed projection extending into said longitudinal portion of the slot in the drive sleeve rearwardly of said first fixed projection.

9. In a writing instrument, a casing including a forward section and a rear section telescopically slidable on the forward section, said forward section including a nose member having a reduced dimension opening at its forward writing end, a body sleeve detachably secured to said nose member and extending rearwardly therefrom, said rear section including a drive sleeve telescopically slidable in said body sleeve, said instrument also including a generally cylindrical driven sleeve having a spiral slot and slidably disposed in said drive sleeve, a writing unit having a relatively small forwardly extending writing point and a relatively large rear cylindrical portion fitted in said driven sleeve, the forward end of said body sleeve being of at least as great dimension as said cylindrical portion, and the driven sleeve having a plurality of slots with inwardly bent portions between adjacent slots in engagement with said writing unit for frictionally but removably retaining the writing unit

in the driven sleeve, and the writing unit being thereby movable with said driven sleeve for projection and retraction of the writing point through said opening, and cam means on said casing sections and driven sleeve effective for moving the driven sleeve for projection and retraction of the writing point in response to relative movement between the casing sections.

- 5 10. In a writing instrument, a casing including a forward section and a rear section telescopically slidable relative to each other, said forward section including a nose member of substantial thickness and having a small diameter bore at its forward writing end and a larger diameter bore adjacent its rear end, and a shell-like body sleeve detachably connected to the rear end of said nose member and extending rearwardly therefrom, said rear section including a shell-like drive sleeve slidable in said body sleeve and having a slot with a longitudinal portion and a circumferential portion at the forward end of the longitudinal portion, a writing unit having a writing point and slidably disposed in said drive sleeve for projection and retraction of its point 15 through said small diameter bore, said writing unit having a spiral slot adjacent its rear end, said body sleeve having a projection adjacent its rear end extending into both of said slots, and said unit having a projection extending into said longitudinal portion of the slot in the drive sleeve rearwardly of said first projection.
